UNITED STATES PATENT OFFICE.

THEODORE BARNES, OF DES MOINES, IOWA.

COMBINED SWITCH AND PERMUTATION-LOCK.

1,329,693.

Specification of Letters Patent.

Patented Feb. 3, 1920.

Application filed November 16, 1917. Serial No. 202,347.

To all whom it may concern:

Be it known that I, THEODORE BARNES, a citizen of the United States, residing at Des Moines, in the county of Polk and State of Iowa, have invented certain new and useful Improvements in Combined Switches and Permutation-Locks, of which the following is a specification.

My invention relates to switches, adapted for use upon automobiles or the like, while not necessarily restricted to such use, and having its operation controlled by a permutation lock.

An important object of the invention is to provide apparatus of the above mentioned character, which may be conveniently operated by the authorized user, in an expeditious manner.

A further object of the invention is to provide apparatus of the above mentioned character, parts of which may be conveniently assembled and separated, the separation of the parts being dependent upon the operation of the permutation lock.

A further object of the invention is to provide apparatus of the above mentioned character, which is simple in construction, inexpensive to manufacture, strong and durable.

Other objects and advantages of the invention will be apparent during the course of the following description.

In the accompanying drawings forming a part of this specification and in which like numerals are employed to designate like parts throughout the same.

Figure 1 is a side elevation of apparatus embodying my invention, the outer casing being shown in section,

Fig. 2 is a vertical longitudinal sectional view taken on line 2—2 of Fig. 1,

Fig. 2a is an end elevation of a turning shaft and associated elements,

Fig. 3 is a horizontal longitudinal sectional view taken on line 3—3 of Fig. 2,

Fig. 4 is a side elevation of the stationary contact carrying member of the switch, parts being shown in section,

Fig. 5 is a similar view of the rotatable contact carrying member and switch, together with associated elements,

Fig. 6 is a transverse sectional view taken on line 6—6 of Fig. 1,

Fig. 7 is a similar view taken on line 7—7 of Fig. 1,

Fig. 8 is an inner face view of the apparatus shown in Fig. 5,

Fig. 9 is a fragmentary longitudinal sectional view through the permutation lock, parts being omitted,

Fig. 10 is an end elevation of the inner stationary tubular member of the lock,

Fig. 11 is a transverse sectional view taken on line 11—11 of Fig. 9,

Fig. 12 is a similar view taken on line 12—12 of Fig. 9, parts being omitted, and,

Fig. 13 is a central longitudinal sectional view through the inner relatively stationary tube of the permutation lock, parts being removed.

In the drawings, wherein for the purpose of illustration is shown a preferred embodiment of my invention, attention being called at first to Figs. 1, 2, 3, 4, and 5, the numeral 15 designates a base-plate. This base-plate 75 is provided with a central cylindrical opening 16, receiving therein an outer tubular rotatable and reciprocatory member 17, the forward end of which is provided with a recess or chamber 18, normally covered by 80 a cap 19, preferably having screw-threaded engagement therewith, as shown at 20. The outer tubular member 17 is provided at its inner end with an annular gear 21, as shown more particularly in Figs. 9 and 11. The 85 tubular member 17 has a longitudinal opening 17', formed therein, as shown.

Disposed within the outer tubular member 17 is an inner stationary tubular member 22, provided at its forward end with a flange 90 23, and at its rear end with a flange 24. The flange 24 extends outwardly beyond the inner end of the outer tubular member 17, as shown. The tubular member 22 has an opening 22', to register with the opening 17'. 95

Surrounding the outer tubular member 17 is a stationary annular holding flange 25, (Fig. 2) preferably formed integral with the base 15. The flange 25 is provided with a shoulder 26, to contact with the flange 24, 100 as shown. This shoulder constitutes the end wall of an enlarged screw-threaded bore 27 of the flange 25, provided with a longitudinal groove 28, for the reception of a key or extension 29, formed upon the flange 24. It 105 is thus apparent that means are provided

to lock the inner tubular member 22 to the flange 25, against rotation with respect thereto.

The numeral 30 designates a locking ring, 5 which is L-shaped in cross-section and screw-threaded to engage within the screw-threaded bore 27, as shown. This locking ring serves to hold or lock the inner tubular member 22 within or to the flange 25.

10 The numeral 31 designates an insulating sleeve, projecting into the inner tubular member 22, and carried by an insulating head 32, arranged upon the flange 24 and clamped thereto by the ring 30, as shown. 15 The head 32 is provided with an opening 33, for the purpose to be described.

The numeral 34 designates a casing, constituting the body portion of the apparatus, and this casing is secured to the base 15 by 20 means to be described. The casing 34 may be attached to a stationary support or dash 35, by means of brackets 36 or the like.

Arranged within the casing 34, at diametrically opposite points, are brackets 37, 25 attached thereto, as shown at 38. These brackets are approximately L-shaped and are provided at their ends with flanges 39 and 40, as shown.

The numeral 41 designates an approximately U-shaped bracket (see Fig. 2) having transverse end portions 42 and 43. The end portion 42 is attached to a lock or flange 44, formed upon the inner side of the base 15, by means of a screw 45 or the 30 like. The end portion 43 is provided with an extension or lip 46, adapted to be inserted within an opening 47, formed in a lock or flange 48, carried by the inner side of the base 15. It is thus apparent that the 35 bracket 41 is securely attached to the base 15. Attached to the longitudinal portion of the bracket 41 are guide pins or rivets 49 (see Figs. 2 and 8) operating within longitudinal slots 50, formed in a pair of reciprocating bolts 51. These bolts have their 40 inner ends reduced for substantially one-half of their width, providing extensions 52, arranged side by side, overlapping and carrying laterally extended heads 53. One 45 head 53 is provided with a screw-threaded opening to receive the reduced screw-threaded portion of a screw 54, while the other head 53 is provided with an enlarged smooth opening for receiving a smooth portion 50 of the screw. A compressible coil 55 is arranged between the heads 53, thus tending to force the same away from each other, and draw the inner ends of the bolts 50 inwardly. The screw 54 is equipped 60 with a head 56, and access is had to this head through an opening 57, in the casing. The screw 54 carries a stop nut 54', as shown. The extensions 52 are provided with semi-circular openings 58 (see Fig. 3) adapted 65 for registration, when the bolts 50 are in the

outer holding position for the purpose to be described. The outer ends of the bolts 51 are adapted to engage inwardly of or behind the flanges 39 (see Fig. 2) thereby serving to lock the base 15 and elements carried thereby, to the casing 34.

Means are provided to normally lock the outer tubular member 17 against forward longitudinal movement, comprising a rod 59, extending longitudinally within and 75 through the inner relatively stationary tubular member 22 and having a swiveled connection with the recess or chamber 18, as shown at 60. The rod 59 is provided with laterally extending lugs or bits 61 and 80 62. The rod 59 is provided upon its rear end with a lock-extension 59', to enter the registering openings 58, as shown in Fig. 3.

The numeral 63 designates tumblers (Fig. 2) which are pivoted within the stationary 85 tubular member 22. These tumblers have key-hole openings 64, adapted for the reception of the rod 59 and the bits 62 thereof. Arranged between the rotatable tumblers 63 are stationary spacing rings or washers 90 65, (see particularly Fig. 12) provided upon their peripheries with tongues or keys 66, adapted to enter a longitudinal groove 67, formed in the stationary tubular member 22, as clearly shown in Fig. 13. The numeral 95 68 designates a relatively stationary combination setting member, having a flanged hub 69, provided with a key-hole opening 70, adapted for the reception of the inner bit 62 and the next bit 61. Before the bit 100 62 moves completely out of the key-hole opening 70 the bit 61 is moved therein, whereby the rod 59 is permanently prevented from rotating upon its longitudinal axis. The member 68 is provided upon its periphery with lugs or keys 71 (see Fig. 10), 105 adapted for insertion within grooves 72 formed upon the interior of the stationary tubular member 22. It is obvious that before the rod 59 can be moved forwardly, the tumblers 63 must all be turned so that their key-hole openings are in alignment with the key-hole opening 70 and by turning the member 68 to shift the radial position of its key-hole opening 70, the position 110 that the tumblers must be moved to bring all key-hole openings into alignment, is accordingly changed. By this means the combination may be changed or set.

The switch apparatus comprises an annular rotatable contact carrying member 73, having a flange 74, pivoted upon the stationary flange 25. A portion of the flange 74 is cut away for receiving a segmental gear 75, operating within a slot or opening 76 125 formed in the stationary flange 25, as shown in Fig. 2. This slot is made sufficiently long to permit of the desired extent of movement of the member 73. The teeth of this gear 75 project into the flange 25 and are 130

adapted for engagement with the teeth 21, when the outer tubular member 17 is drawn forwardly, whereby the annular contact carrying member 73 will turn upon the turning movement of the member 17. This contact carrying member 73 is provided with any suitable number of contact segments 77 disposed upon the inner and outer sides thereof, and adapted to be moved into electrical contact with pairs of coacting contact strips 78, attached to binding posts 79.

These binding posts are secured to a stationary member 80, formed of insulating material, and rigidly secured to the flanges 40, as shown at 81. The binding posts are adapted for connection with wires (not shown) which may be passed in through an opening 82 in the casing 34.

The numeral 83 designates binding posts, having connection with contacts 84, as shown in Fig. 3, and these contacts normally engage contacts 85, extending forwardly for providing terminals 86. These terminals are adapted to be electrically connected by a contact segment or ring 87, carried by the rod 59 and insulated therefrom. It is thus apparent that the circuit will be closed when the rod is moved forwardly sufficiently to bring contact 87 into engagement with contacts 86.

The numeral 88 designates a hand wheel, secured to the shaft 88' (see Fig. 2^a), pivoted to the base 15 and extending inwardly beyond the same. Rigidly secured to the inner end of this shaft 88' is a forked-crank 89', shown more clearly in Fig. 2^a. This forked-crank is adapted to project into a recess in the member 74 and to engage with a pin 90', rigidly secured to the outer portion of the member 74. When the member 74 is in the normal position, the forked-crank 89' will engage with the pin 90' and the hand wheel 88 will be capable of turning the member 74 for a restricted distance, which may be employed to turn on or off certain circuits, without operating the combination, provided the member 74 is in the starting or neutral position.

The apparatus shown and described is particularly well adapted for opening and closing circuits employed upon an automobile. Thus the contacts 86 and 87 may be employed to open and close the circuit for starting the engine while the other contacts 55 may be employed for controlling the various circuits for the lights and the like. However, it is obvious that the invention is in no sense restricted to this particular use.

In assembling the various parts of the apparatus, the screw 54 is unscrewed, and this unscrewing movement is limited by the nut 54', contacting with one head 53. As the screw is unscrewed, the spring 55 forces the heads 53 apart, whereby the ends of the bolts 51 become positioned inwardly of the

flanges 39. The base 15 may then be placed upon the casing 34, and the rod 59 should be in the forward position with the combination open. A screw driver may now be passed through the opening 57 and the screw turned to screw the same up whereby such screw will serve to move the heads 53 toward each other, and the bolts 51 will be moved outwardly so that their outer ends catch behind the flanges 39, thereby serving to lock the base to the casing. When the rod 59 is shifted to the rear or inner position, the extension 59' thereof will pass into the openings 58, which are now in registration. If the combination is now set or locked it is obvious that the bolts 51 cannot be moved inwardly, by the expansion of the spring 55, if the screw 56 is unscrewed, whereby the base 15 and casing 34 are locked together prior to the operation of the combination.

In the operation of the apparatus, the rotatable tumblers 63 are turned until the proper reference characters 63' constituting the correct combination, are brought in alignment, at which time the bolt 59 may be moved forwardly. The longitudinal movement of the bolt may operate a circuit and various other circuits may be operated by turning the tubular member 17, upon its longitudinal axis.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. In apparatus of the character described, a casing, a base for covering one end of the casing, switch apparatus arranged within the casing, a pair of reciprocatory bolts connected with the base and adapted for engagement with portions of the casing to lock the casing and base together and having coacting recesses adapted to be brought into registration, means connected with the bolts to move them, a member to operate the switch apparatus, and a permutation lock to control the action of the member and including an element adapted to enter the recesses of the reciprocatory bolts to hold them against movement.

2. In apparatus of the character described, a casing, a base for covering one end of the casing, switch apparatus arranged within the casing, a movable bolt connected with the base and adapted for engagement with a portion of the casing to lock the casing and base together and having an opening formed therein, means connected with the bolt to move it, a member adapted to operate the

switch apparatus, and a permutation lock to control the action of the member and including an element adapted to enter the opening of said bolt and hold said bolt in locking position.

3. In apparatus of the character described, a casing, a base for covering one end of the casing, switch apparatus arranged within the casing, a movable bolt connected with the base and adapted for engagement with a portion of the casing to lock the casing and base together and having an opening formed therein, means connected with the bolt to move it, a relatively stationary tubular member connected with the base, a movable outer tubular member arranged upon the inner tubular member and adapted to actuate the switch apparatus, tumblers arranged within the inner tubular member and having key-hole openings, and a rod extending through the tumblers and having bits to enter the key-hole openings of the tumblers and provided with an extension to enter the opening of the bolt and hold said bolt in locking position.

4. In apparatus of the character described, a casing, a relatively stationary contact carrying member disposed within the casing, a turning contact carrying member arranged within the casing in co-operative relation to the first named contact carrying member co-acting contacts secured to said members, a rotatable and longitudinally movable member, means to connect the rotatable and longitudinally movable member with the turning contact carrying member when the turning contact carrying member has been moved longitudinally in one direction, and means for controlling the longitudinal movement of the rotatable and longitudinally movable member.
5. In apparatus of the character described,

a casing, a relatively stationary contact carrying member disposed therein, a turning contact carrying member arranged with in the casing in co-operative relation to the first named contact carrying member, coacting contacts secured to said members, a gear connected with the turning contact carrying member, a rotatable and longitudinally movable member, a gear carried by the rotatable and longitudinally movable member to engage with the first named gear in one longitudinal position of said movable member, and means for controlling the longitudinal movement of the rotatable and longitudinally movable member.

6. In apparatus of the character described, a casing, a base secured to the casing and provided with an interior annular flange having an opening formed therein, a stationary contact carrying member arranged within the casing, a turning contact carrying member pivoted upon the annular flange, coacting contacts carried by the contact carrying members, a clutch element connected with the turning contact carrying member and projecting through the opening of the annular flange, a reciprocatory and rotatable member arranged to operate with in the annular flange, a coacting clutch element carried by the reciprocatory rotatable member, and engaging said first clutch element in one longitudinal position of said reciprocatory rotatable member, and means for controlling the reciprocatory movement of the reciprocatory and rotatable member.

In testimony whereof I affix my signature in presence of two witnesses.

THEODORE BARNES.

Witnesses:
